COLUMBIA PLANOGRAPH CO., WASHINGTON, D. C.

UNITED STATES PATENT OFFICE.

HARRY GREENWOOD, SR., OF BARNESBORO, PENNSYLVANIA.

CHAIR ATTACHMENT.

1,088,982.

Specification of Letters Patent.

Patented Mar. 3, 1914.

Application filed May 23, 1913. Serial No. 769,544.

To all whom it may concern:

Be it known that I, HARRY GREENWOOD, Sr., a citizen of the United States, residing at Barnesboro, in the county of Cambria and 5 State of Pennsylvania, have invented a new and useful Chair Attachment, of which the following is a specification.

The present invention relates to improvements in chair attachments, one object of 10 the present invention being the provision of an attachment adapted to be particularly used in connection with a barber or dentist's chair, the same being so disposed as to readily carry the instruments or other paraphernalia necessary for immediate use, adjacent to the chair, the same being so constructed and attached, as to permit of the ready swinging and locking of the same in any desired adjustment. 15 A further object of the present invention is the provision of a novel form of supporting means for a tray or rack, the same being vertically adjustable and horizontally rotatable, the means for vertically adjusting 20 the same also constituting a locking means to hold the same in any fixed adjustment, in or out of use.

With the foregoing and other objects in view which will appear as the description 25 proceeds, the invention resides in the combination and arrangement of parts and in the details of construction hereinafter described and claimed, it being understood that changes in the precise embodiment of the 30 invention herein disclosed can be made within the scope of what is claimed without departing from the spirit of the invention.

In the drawings—Figure 1 is a perspective view of the present attachment shown 35 connected to a barber's chair, a portion only of the chair being shown in perspective. Fig. 2 is a detached view of the present attachment, the article supporting member of which is shown in transverse cross section. 40 Fig. 3 is a bottom plan view of the main supporting shelf of the device. Fig. 4 is an enlarged detail sectional view through the chair connecting and carrying member and the telescopic supporting members of 45 the attachment. Fig. 5 is a perspective view of a modified form of attaching device. Fig. 6 is a side elevation of the attachment 50 provided with a sub-platform to prevent the too far positioning therewithin of bottles or the like. 55

Referring to the drawings, the numeral

1 designates a metal clamping device, whose long terminal 2 is connected to the chair C in any well known manner, while the short terminal 3 is the resilient terminal and is 60 held so as to produce a proper clamping effect upon the sleeve by means of the screw 4. Disposed for vertical adjustment within the clamp 1 is a tubular support 5, whose upper edge is provided with the ridges 6 65 and the depression 7, the purpose of which will presently appear. Mounted telescopically, both for vertical and rotating movements within the tubular support 5 above the upper convolute end thereof is a cylindrical support 8, provided with a plurality of transverse apertures 9 therethrough adjacent its lower end. Disposed removably within these apertures 9 is a headed pin 10, which is disposed to project beyond the 70 outer circumference of the rod 8 and fit within the diametrically disposed recesses 6 of the member 5, and thus hold the rod 8 against turning. It is evident that the rod 8 may be turned manually but that the positioning of the pin within the diametrically disposed recesses 6 will tend to hold the same against accidental movement. The upper end of rod 8 is provided with the arm 11, which is secured to and carries the circular shelf or platform 12, which has upstanding concentrically thereof the bottle supporting member 13, whose upper end is concaved as at 14 for the antifrictional ball bearing 15. Disposed to fit upon the upper 80 end of the support 13 and incase the ball 15, is a socket member 16, which is connected to and carries the shelf 17. This shelf 17 is provided with apertures 18 for the reception of bottles or the like while disposed there- 85 through, as clearly shown in Figs. 1 and 2, is a slot 19, which is in registration with the outlet end of the paper carrying member 20, there being disposed upon the upper face of the shelf 17 in parallel with the slot 19 a 90 paper cutter 21. A roll 25 of paper is placed within the container 20 and has its free end directed through the slot 19 above the cutter, as clearly shown in Fig. 2, so that paper may be torn therefrom as desired. 95 When it is desired to provide a sub-platform or shelf below the platform 17 the device is constructed and arranged as shown in Fig. 6, a sub-shelf 17' being employed.

In the form of support shown in Fig. 5, 100 a plate 22 is provided and has the parallel apertured lugs 23, by means of which the

same may be attached to the arm or any portion of a chair, the same displacing the terminal 2 of the clamp device 1. The plate is slotted at 24 and has slidably mounted therein the guiding pin 25, the upper one 26 of which is a clamping device and both of which pierce the upright portion 27 of the sleeve engaging bail or arm 28. A clamp 29 is carried by the bail portion for locking the 10 same to the sleeve 5. Any number of shelves 17 may be used in superposed relation.

From the foregoing description, taken in connection with the drawings, it is evident that a rack or attachment constructed according to the present invention, may be readily attached to a dentist's or barber's chair, and that the shelf containing the various necessities, such as instruments to be used, may be readily positioned thereupon 20 and when desired may be moved to and from the position above the seat portion of the chair, the pin 10 and the corrugated portion of the tubular member 5 providing a means for locking the same in either position 25 against accidental displacement yet permitting the same to be readily rotated to assume either one of the desired positions. By means of the pin 10 and the apertures 9, the arm carrying rod 9 may be adjusted verti-

cally to any desired height so as to bring 30 the article supporting member thereof into ready access for various heights of operatives.

What is claimed is:

A chair attachment, including a tubular 35 support, the upper edge of which is provided with a plurality of even numbered depressions and ridges, an arm having a tubular shank which is vertically slidable and rotatable within the tubular support, the lower 40 end thereof being provided with a plurality of diametrically disposed apertures there-through, a pin insertible through any one of said apertures and of greater length than the diameter of the rod, said pin being disposed to seat within diametrically opposed recesses at the upper end of the tubular member to lock the arm against rotation, and an article carrying shelf connected to the upper 45 end of the supporting arm. 50

In testimony that I claim the foregoing as my own, I have hereto affixed my signature in the presence of two witnesses.

HARRY GREENWOOD, Sr.
